CORSELETTE OR SIMILAR ARTICLE

Mathilde Riesenfeld, New York, N. Y.

Application May 26, 1955, Serial No. 36,234

Term of patent 3½ years

(Cl. D20—2)

Fig. 1.

Fig. 2.

I claim:

The ornamental design for a corselette or similar article, substantially as shown.
